FOUNTAIN SHAVING BRUSH

Filed July 24, 1924

UNITED STATES PATENT OFFICE.

LOUIS DAVIS, OF EAST NASHVILLE, TENNESSEE.

FOUNTAIN SHAVING BRUSH.

Application filed July 24, 1924. Serial No. 728,002.

To all whom it may concern:

Be it known that I, LOUIS DAVIS, a citizen of the United States, residing at East Nashville, in the county of Davidson and State 5 of Tennessee, have invented certain new and useful Improvements in Fountain Shaving Brushes, of which the following is a specification, reference being had to the accompanying drawings.

10 This invention relates to certain improvements in fountain shaving brushes and it is an object of the invention to provide a novel and improved device of this general character especially designed and adapted for 15 use in connection with shaving cream and wherein the various parts comprised therein can be readily replaced.

Another object of the invention is to provide a novel and improved device of this 20 general character which is highly sanitary and is therefore particularly adapted for use by physicians and surgeons when it is necessary to shave the affected portion of the body before an operation.

25 The invention consists in the details of construction and in the combination and arrangement of the several parts of my improved fountain shaving brush whereby certain important advantages are attained and 30 the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings; wherein:—

40 Figure 1 is a view in perspective illustrating a brush constructed in accordance with an embodiment of my invention, with one of the caps shown detached;

45 Figure 2 is a longitudinal sectional view taken through the structure as illustrated in Figure 1, with the outer cap omitted, the cap or cover for enclosing the bristles or hairs of the brush being indicated by broken lines;

50 Figure 3 is a fragmentary sectional view illustrating the manner of applying the tube within the member or body;

Figure 4 is a view in top plan of the head of the brush as herein disclosed;

55 Figure 5 is a view in perspective of the

cap or cover for enclosing the bristles or hairs of the brush;

Figure 6 is a fragmentary sectional view taken through the lower portion of the cap illustrated in Figure 5.

As disclosed in the accompanying drawings, A denotes an elongated tubular member constituting the main body of my improved brush and which has one end portion 1 enlarged providing an internal annular shoulder 2 at the inner end of said enlarged portion. The brush B includes a head 3 which threads within the enlarged portion 1 of the member or body A, said head being provided with an outstanding 65 annular flange 4 to provide means whereby the brush B and the member or body A may be readily connected or disconnected as required. The peripheral surface of this flange 4 is milled or otherwise roughened 70 to facilitate its use.

Insertible within the member or body A is a tube C the walls of which being of soft rubber and having one end open, said open end being defined by an outstanding flange 6 80 which contacts with the internal shoulder 2 when the tube is in applied position with respect to the member or body A, the head 3 of the brush B also engaging said flange 6 when the brush is in applied position 75 whereby the tube is effectively held in applied position.

The tube C is of a length, when applied, to have its closed end extend beyond the outer end of the member or body A, said 90 closed end as herein disclosed being substantially semi-spherical in form. The inner face of the head 3 of the brush B is provided with a depression or cavity 7 which in the assembly of the brush is in register 95 with the open end of the applied tube C. Disposed through the head 3 of the brush and preferably leading from the axial center of the depression or cavity 7 thereof and discharging from the bristles 8 of the 100 brush is an outlet port 9.

In threaded engagement with the outer end of the member or body A is the cover or cap 10 which closely conforms to the extended closed end portion of the tube C and in threaded engagement with the head 3 of the brush B outwardly of the flange 4 is a cap or cover 11 to protect the bristles 8 when the brush is not in use.

In practice, the tube C is inserted into the 110

member or body A through the inner end thereof after the brush B has been separated therefrom. The outer surface of said tube preferably having talcum or the like applied thereto to facilitate such operation. The shaving cream or the like is then placed within the tube C care being exercised not to fill beyond the level of the flange 6. The depression or cavity 7 in the head 3 of the brush B is then filled with the cream and the brush attached to the member or body A.

To use the brush the bristles 8 are suitably moistened and then the cover or cap 10 is removed and pressure applied by a digit of the hand upon the outer or extended closed end portion of the tube C; this will result in forcing the cream or the like through the outlet port 9 to the bristles 8 whereby the lather may be formed upon the face or other parts of the body as desired. As the cream or the like is consumed the outer or closed end portion of the tube C is pressed inwardly until all of the cream or the like within the tube C and in the depression or cavity 9 is emptied therefrom. It is to be noted that the member A prevents the tube C from having lateral expansion and thereby facilitating the requisite discharge through the port 9 as the outer portion of the tube C is collapsed as a result of the pressure imposed upon the outer end thereof. The efficiency of the tube C is further facilitated in view of the fact that it is of the same diameter from its open end to its rounded closed end.

My improved brush is highly sanitary as the cream or the like at all times is hermetically sealed and therefore immune from infection and contamination. This feature of the brush due to its convenience makes it particularly desirable for use by physicians, surgeons, nurses and the travelling public.

All of the parts of my improved brush with the exception of the tube C and the bristles or hairs 8 are preferably made of hard rubber and whereby the brush in its entirety is substantially indestructible.

As a tube C becomes worn or otherwise unfit for use it may be readily replaced with a new tube.

The cover or cap 11 in its outer end wall is provided with a relatively large opening 12 and in its side walls with the smaller open-

ings 14. These openings 12 and 14 are for the purpose of ventilation and will permit 55 the bristles or hairs 8 to readily dry after the cap 11 has been applied.

From the foregoing description it is thought to be obvious that a fountain shaving brush constructed in accordance with 60 my invention is particularly well adapted for use by reason of the convenience and facility with which it may be assembled and operated, and it will also be obvious that my invention is susceptible of some change and 65 modification without departing from the principles and spirit thereof and for this reason I do not wish to be understood as limiting myself to the precise arrangement 70 and formation of the several parts herein shown in carrying out my invention in practice except as hereinafter claimed.

I claim:—

A device of the class described comprising, 75 a tubular member open at both ends, said member adjacent to one end being provided with an internal shoulder, a brush head mounted in the tubular member outwardly of the internal shoulder, the inner face of the brush head being provided with a cavity, 80 a tube of yieldable material snugly fitting within the tubular member, one end portion of the tube being open, said open end portion being provided with an outstanding flange 85 for contact with the internal shoulder of the tubular member, the head serving to clamp the flange of said yieldable tube against said shoulder, the brush head being provided with a discharge port leading therethrough from 90 the cavity, the yieldable tube being of a length to have its opposite closed end portion extending beyond the outer end of the tubular member, the outer portion of the bore of the tubular member being of a diameter to permit the insertion therein 95 through said outer end a digit of a hand to collapse the tube in a direction lengthwise thereof and lengthwise of the tubular member, said tubular member holding the tube against lateral expansion when pressure is 100 imposed upon the outer end of the tube, said tube being of the same diameter from its open end to its closed end.

In testimony whereof I hereunto affix my signature.

LOUIS DAVIS.
